UNITED STATES PATENT OFFICE.

EARLE G. ALDEN, HARRY B. ALDEN, AND JOHN P. SQUIRES, OF DENVER, COLORADO.

LOOSE-LEAF BINDER.

Application filed January 17, 1924. Serial No. 686,870.

To all whom it may concern:

Be it known that we, EARLE G. ALDEN, HARRY B. ALDEN, and JOHN P. SQUIRES, all citizens of the United States of America, residing at Denver, in the county of Denver and State of Colorado, have invented certain new and useful Improvements in Loose-Leaf Binders, of which the following is a specification.

10 This invention relates to loose leaf binders of the type described in detail in the application of one of the present inventors, filed Oct. 16, 1922, Serial No. 594,900, patented Feb. 19, 1924, Patent No. 1,483,862, and has 15 for its principal object the provision, in a binder of this character, of means whereby each of arches or loops of the binder will come in perfect contact with its standard, irrespective of the relative position of each 20 of the other loops.

Another object of the invention is to provide means for aligning the loops with their standards and for locking them in alignment.

25 A further object is to so construct and arrange the trigger or releasing mechanism that it will occupy a minimum of space in order that the base board of the binder need not be made unnecessarily thick.

30 A still further object of the invention is to provide means in the binder cover for insuring the proper spacing of the openings therein, and for protecting the cover from injury at these openings.

35 Other objects and advantages reside in the detail construction of the invention, which result in simplicity, economy, and efficiency, and which will become more apparent from the following description.

40 In the following detailed description of the invention reference is had to the accompanying drawing which forms a part hereof. Like numerals refer to like parts in all views of the drawing and throughout the description.

45 In the drawing:

Fig. 1 is a longitudinal vertical section through the invention.

50 Fig. 2 is a fragmentary plan view, partly in section, said section being taken on the line 2-2, Fig. 1.

Fig. 3 is an enlarged detail view of the trigger mechanism. The mechanism being shown in "open" position.

55 Fig. 4 is a detail view of the joint between

the fixed and movable portions of the binding loops.

Let the numeral 10 designate a base board to one end of which the operating mechanism is attached. A binding 11 of a suitable material, such as canvas, corduroy, leather, etc., surrounds the base board 10 and the operating mechanism.

The operating mechanism is contained between two plates, the bottom plate, 12, extends back under and is secured to the base board 10 by means of screws 13. The top plate, 14, is secured to the bottom plate 12 by means of suitable screws 15, and is held in spaced relation therewith by spacer 65 washer 16.

A series of fixed, vertical standards 17 are secured in the bottom plate 12 and project upward through the top plate 14. The standards 17 are also provided with spacer 75 washers 18.

A similar series of rotatable looped standards 19 are journaled in the plates 12 and 14 and project upward therefrom to coact with the fixed standards 17. Secured to the 80 standards 19, between the plates 12 and 14, are levers 20, all of which are operated by means of common connection bar 21.

A spring 27 forces a pivoted lever or trigger 22 into engagement with a notch 23 in the edge of the connecting bar 21, as shown in Fig. 3, when the loops have been turned to the open position, as shown in broken line at 24, and locks the loops open. The trigger 22 is provided with a button 25, which operates in an arcuate slot 26 in the plate 14, and by means of which the trigger is released from engagement with the bar 21. By having the trigger operate horizontally and engage the edge of the bar 21, a great saving 90 of vertical space is obtained which allows the base board 10 to be made much thinner than when the lever operates vertically and engages notches in the top of the bar 21, as in the previous application.

100 It will be noted that only one of the levers 20 is directly pivoted to the bar 21, it being shown at 28. All other levers have their pivot pins operating in slotted holes 29, in the bar 21. The purpose of this is to accomplish the primary object of our invention, viz, to allow each of the loops to come into contact with its standard independent of the contact of each of the other loops.

110 It was found practically impossible to

2

bring all of the loops of a series into contact when the levers were all directly pivoted, as shown in the said previous application, for if one of loops should contact with its standard before the others, because of injury or imperfect manufacture, it would prevent all of the others from coming into contact. With the use of the slotted holes 29 and by providing each lever operating in 10 a slotted hole with an independent spring 30, this difficulty has been eliminated for each loop is allowed an independent radius of operation which allows its spring to draw it into contact regardless of the position of 15 the connecting bar 21.

A spring 31 operates the bar 21 and the loop whose lever is directly pivoted thereto.

It has been found, especially where the standards are long and the book is thick, 20 that some means are required for drawing the extremities of the standards into engagement and holding them there. We have accomplished this by cutting the extremities so as to form a lap joint, as shown 25 in Fig. 4, and by providing one of the coacting laps with a tapered pin 32, which engages an opening 33 in the other of the coacting laps. Should the two contacting extremities be slightly out of alignment when 30 the pin contacts with the opening 33, it, being tapered, will draw the parts into alignment as it passes into the opening.

A cover 34 is provided to enclose the bound sheets, designated at 35. The cover 35 is similar to that in the said copending application with the exception that a metal bar 36 is bound into the extremity of said cover. The bar 36 has openings which register with the spacing of the standards 12 40 and through which they are passed. It prevents damage to the cover by the standards and insures the proper spacing of the openings therein.

While specific forms of the improvements have been described and illustrated herein, 45 it is desired and understood that the same may be varied, within the scope of the appended claims, without departing from the spirit of the invention.

Having thus described our invention what 50 we claim and desire to secure by Letters Patent is:—

1. A loose-leaf binder comprising rotatable arch standards; a lever arm secured to each of said standards; a common connecting 55 bar, provided with slotted holes; pivot pins in said lever arms traveling in said slotted holes and an independent spring acting on each of said cranks.

2. A loose-leaf binder comprising a housing; coacting fixed and rotatable standards carried on said housing; a common connecting bar connecting said rotatable standards and having a notch formed in the edge thereof and a horizontally-movable pivoted 60 lever engaging, at its one extremity, in said notch when the rotatable standards are in the open position and projecting, at its other extremity, through an opening in said housing. 65

3. A loose-leaf binder comprising fixed standards; rotatable standards coacting therewith; lever arms secured to said rotatable standards; a connecting bar connecting the extremities of said lever arms, said 70 connection being sufficiently flexible to allow each standard to move through a relatively small arc independently of the others and sufficiently rigid to cause all said arch standards to operate simultaneously through a 75 relatively greater arc.

In testimony whereof, we affix our signatures.

EARLE G. ALDEN.
HARRY B. ALDEN.
JOHN P. SQUIRES.
